UNITED STATES PATENT OFFICE.

FRANK A. HUNTINGTON, OF SAN FRANCISCO, CALIFORNIA.

FEED AND SET WORKS FOR SAW-MILLS.

SPECIFICATION forming part of Letters Patent No. 245,632, dated August 16, 1881.

Application filed August 30, 1880. (No model.)

To all whom it may concern:

Be it known that I, FRANK A. HUNTINGTON, of the city and county of San Francisco, in the State of California, have made and invented certain new and useful Improvements in Feed and Set Works for Saw-Mills, which invention is fully set forth and described in the following specification and the accompanying drawings therein referred to.

10 My invention relates to improvements in mechanism for feeding and setting logs in saw-mills. The mechanism by which I obtain these results is fully set forth and illustrated in the following description and the drawings accompanying it.

15 In the said drawings, Figure 1 is a front elevation of the stationary frame-work that supports the saw-arbor and the mechanism adjacent thereto and not connected with the log-carriage. Fig. 2 is a plan view of the same, showing also a portion of the log-carriage and its track. Fig. 3 is a detail view of the friction-wheel and its connections. Fig. 4 is an elevation in transverse section through the log-carriage, showing the head-block and its automatic setting mechanism. Fig. 5 is a plan view of Fig. 4. Figs. 6, 7, 8, and 9 are detail views of the machine.

20 The frame-work A has suitable bearings for both ends of the saw-spindle b, and also for an intermediate shaft, C, to which motion is continuously imparted from the spindle by means of the cone-pulleys D E and the belt f. The spindle has the driving-pulley G upon its outer end, and is the principal shaft of the feed mechanism, besides operating the saw. Between these two shafts b C, I arrange a long shaft, H, the outer end of which turns in a bearing, i', fixed on the frame beneath the carriage I, and carries a pinion, i, that engages with a rack, i², on the under side of the carriage, while the other end of this shaft is mounted in a swinging bearing or box, J, upon the frame A, so that this end of the shaft can be moved laterally, the object of which will be seen more clearly hereinafter. At this end of the shaft, also, I fix a large wheel, K, having a rim with a frictional surface designed to engage and run in contact with a friction-pulley, L, on the shaft C, so as to be driven thereby.

25 By this means the shaft H is rotated and

caused to move and feed the carriage forward against the saw.

In order to effect a reverse movement of the shaft H, so that the carriage can be run back 55 from the same forward movement or rotation of the two shafts b C, I interpose the loose pulley N on the end of a suspended arm, O, on the side of the frame, so as to run in contact with the pulley M on the shaft b and the wheel K. 60 The contact of these three wheels with one another transmits the motion of the driving-shaft b to the shaft H, but in a reverse direction, so that at such time the pinion of the shaft H will run the carriage I backward and carry the 65 log away from the saw.

For the purpose of bringing and holding the friction-wheel K in contact with the pulley N, to "feed back" the carriage, I mount the inner end of the shaft H in the swinging box J, as 70 before mentioned, so that a slight lateral movement can be given to the wheel K, sufficiently to bring it against the pulley N. This lateral movement is given to the wheel by means of the rock-shaft Q, its upright hand-lever P, the 75 arm r upon the rock-shaft, and the connecting-rod r', pivoted to the end of the arm r and attached to the pivoted bar v', carrying upon its lower end the box J for the shaft H. This bar v' is pivoted at J' to the frame-work A. 80 These parts are so arranged that the lateral movement required for the wheel K is very slight, and by pressing upon the lever P in a direction as indicated by the arrow, Fig. 1, the wheel K and pulleys M N will be brought 85 together and the carriage moved backward. By releasing the lever the wheel K will drop back into position against the pulley L, and the carriage will resume its feeding movement.

The means for setting the logs upon the carriage I, to regulate the thickness of board to be cut, consists of a friction feed device combined with the feed-screw R of the head-block, and arranged to be operated at the backward movement of the carriage. The feed-screw R 90 is geared to a cross-shaft, s, extending alongside of the carriage from one block to the other, by means of the wheel and pinion t t, and this shaft carries and is fixed at one end to a wheel, U, having upon its inner face a projecting 95 flange, w, concentric with the hub of the wheel. Against this side of the wheel and fixed to a

hub or collar which turns freely upon the shaft I arrange an upright rocking-lever, T, having upon its side and in a loose socket a friction-dog, X. The lower end of this dog rests upon 5 the wheel-hub, while its upper end works in contact with the inner surface of the annular flange w. It is placed in position somewhat diagonally to the radius of the wheel, and it has behind it a spring, y, that acts to press 10 forward the upper end. Now, by the forward movement of the lever this dog cramps or binds in between the flange w and the hub, and as the lever is drawn forward the wheel turns with it and rotates the shaft s. At the backward 15 movement of the lever the end of the dog will slip on the flange, and no movement of the wheel U will take place. Thus every forward movement of the lever T will turn the wheel and cause the feed-screws to rotate and 20 move the head-blocks.

The extent of the forward movement of the lever is regulated by the adjustable and automatic mechanism employed to effect the feed at the backward travel of the carriage, and 25 described hereinafter more particularly, while its backward movement is governed by the fixed stop z, projecting from some convenient part of the head-block frame, and the downwardly-projecting arm y' on the hub or collar 30 of the lever.

I produce the forward rotation or feeding movement of the screw-shaft R automatically and at the backward run of the carriage I by means of the lever-arm X', fixed to and projecting from the hub of the lever T in a downward direction and out beyond the wheel U, so as to run upon and over a fixed incline, S, secured to the floor alongside of the carriage.

This arm, then, at the backward run of the 40 carriage, comes in contact with and runs up over the incline, and is raised up thereby the required distance to turn the lever T forward and give motion to the friction feed-wheel U.

I make this incline S capable of adjustment 45 to a greater or less height or inclination by hinging its lower end to the floor-plate S' and by keeping it elevated by means of a movable and adjustable bar, w', beneath its outer end. The length of feed of the log on the carriage 50 is then regulated by varying and setting this incline at a greater or less angle. The end of the arm X' runs in contact with the face of

the incline at both the forward and backward movement of the carriage, and it is kept down thereto either by means of its weight alone 55 or by the action of a spring, as the arm must be brought down to its lowest position each time before the feeding movement takes place, in order to start to feed from the same point or position.

The movements of one feed-screw are communicated to the other head-block by extending the shaft s to and gearing it into that feed-screw at the opposite end of the carriage. In this manner I provide a simple and effective 65 means for reversing the movements of a log-carriage and for feeding up the logs automatically to produce any thickness of board, as the carriage "feeds" or runs back after each cut.

I attach a pull-rod, V, to the upright bar of 70 the lever T, in order to permit the head-blocks to be fed up by hand when desired—as, for instance, when it is required to cut one or more boards of greater thickness than the automatic feed will "set" for. This rod runs through a 75 slot in the fixed bar W, and its forward movement is regulated by the movable stop v, so that its movement can be measured and controlled.

Having thus fully described my invention, 80 what I claim, and desire to secure by Letters Patent, is—

1. In a saw-mill feed and set works, the combination, with the head-block feed-screw R, of the shaft s, geared into the feed-screw, the friction-wheel U, with its annular flange w and hub, and the lever and feed-dog X, controlled and operated by means of the stops z y', and the fixed incline S and arm X', substantially as and for the purposes set forth. 85

2. The combination of the lever-arm X', lever T, friction-dog X, spring y, flanged wheel U, shaft s, wheel and pinion t t, and fixed incline S, constructed and arranged as described, for feeding the screw-shaft R automatically 95 forward at the backward run of the carriage I, as described.

In witness whereof I have hereunto set my hand and seal this 4th day of August, A. D. 1880.

FRANK A. HUNTINGTON. [L. S.]
In presence of—

EDWARD E. OSBORN,
WM. F. CLARK.
